UNITED STATES PATENT OFFICE.

ADOLPH L. DE LEEUW, OF HAMILTON, OHIO, ASSIGNOR TO THE CINCINNATI MILLING MACHINE COMPANY, OF CINCINNATI, OHIO, A CORPORATION OF OHIO.

LOCKING MECHANISM FOR MACHINE-TOOLS.

No. 889,768.

Specification of Letters Patent.

Patented June 2, 1908.

Application filed October 7, 1907. Serial No. 396,240.

To all whom it may concern:

Be it known that I, ADOLPH L. DE LEEUW, a citizen of the United States, residing at Hamilton, in the county of Butler and State 5 of Ohio, have invented certain new and useful Improvements in Locking Mechanism for Machine-Tools, of which the following is a specification.

The main object of my invention is to provide two or more independent locks of the 10 clamp type, actuated through a single control, the principle of the clamps being such, that each is capable of independently and automatically compensating for wear or lost 15 motion without in any wise affecting the operation of the control.

My invention relates more particularly to 20 means for detachably holding and locking a supporting element of a machine such as the overhanging arm of a milling machine. This overhanging arm, as is well understood forms 25 the support of the tool mandrel, and it is desirable to provide means whereby it may be readily removed or locked in position. This overhanging arm is ordinarily supported in 30 two collars formed at the top of the machine frame, and it has been customary to lock the arm independently in the two collars. This arrangement was mechanically disadvantageous and inefficient.

My improvement is directed to the provision of means for simultaneously locking the arm at each end of its support, and also the provision of a strong support and lock which 35 can be readily manipulated, and which will automatically accommodate itself to wear.

The features of my invention are more fully set forth in the description of the accompanying drawings forming a part of this 40 specification, in which:—

Figure 1 is a central vertical section through the support showing the arm in position. Fig. 2 is a section on line x, x , Fig. 1. Fig. 3 is a section on line y, y , Fig. 1.

The support may consist of two independent collars projected upwardly from the frame of the machine above the spindle, but preferably I construct the support in the form of a solid sleeve 1, suitably bored to receive the overhanging arm 2. The sleeve 1 is provided with the pockets 3, 4, forming the 50 housings for the locking mechanism, and the sleeve is also provided with a bore for containing the locking rod 5, which extends

longitudinally through the sleeve casting in 55 parallel line with the arm 2.

Within the pockets 3, 4, are the shoes 6 having segmental faces bearing against the periphery of the arm 2. The upper faces of the shoes 6 are upwardly inclined toward the 60 front of the machine. The rod 5 is provided with the offsets 7, the upper walls of which are inclined at a greater angle to the horizontal than the angle of inclination of the upper faces of the shoes 6. Between the inclined opposing faces of offsets 7 and shoes 6 are placed the rollers 8. These different inclines are employed in a horizontal lock.

The front end of rod 5 is screw threaded and this end is engaged through an adjusting 70 collar 9. When the rod 5 is drawn forward the tapered offsets 7 will force the rollers 8 downwardly upon the segmental shoes 6, and simultaneously clamp these shoes forcibly against the arm 2, thus securely locking it 75 at each end of the sleeve in one movement. The normal tendency of the rollers 8 when free, is to roll down the inclines of the shoes 6, so that when the rod 5 is moved to the opposite position the locks are instantly released. The engagement of the roller bearings 80 between the clamping faces having different degrees of inclination, forms means which automatically compensate for wear or lost motion.

The structure is strong, simple, and easily manipulated.

It is obvious that the principles of the invention can be utilized in connection with any detachable arm or supporting member 90 of a machine which has to be securely locked to the main machine frame, and that the automatic and independent adjustability of the clamp shoes to wear, is applicable to a variety of uses in connection with a member to 95 be locked.

Having described my invention, I claim:—

1. A member to be locked, two or more clamping shoes, an operating rod, the rod and shoes having opposing inclines, and interposed bearing devices, substantially as described.

2. In a machine of the class described, a support, an arm removably held therein, locking shoes held in each end of the support and bearing against the arm, a rod having tapered offsets adjacent to the shoes, bearing rollers interposed between said offsets and

shoes, and means for longitudinally adjusting the said rod in said support, substantially as described.

3. In a machine of the class described, a support, an arm removably held therein, a locking shoe held in each end of the support and bearing against the arm, a rod having tapered offsets adjacent to the shoes, the opposing faces of said shoes and offsets having different angles of inclination, rollers inter-

posed between said inclined faces, and means for longitudinally adjusting the rod, substantially as described.

In testimony whereof, I have hereunto set my hand. 15

ADOLPH L. DE LEEUW.
